CLAIM

The ornamental design for a headlight, as shown and described.

DESCRIPTION

FIG. 1 is a perspective view of a headlight showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

A mirror image of the headlight of FIGS. 1-7 is a second embodiment of the headlight.

The broken lines and de-emphasized portions shown inside the broken lines are for the purpose of illustrating portions of the headlight that form no part of the claimed design. The broken lines and de-emphasized portions form no part of the claimed design.

1 Claim, 4 Drawing Sheets
